UNITED STATES PATENT OFFICE.

HENRY K. SANDELL, OF CHICAGO, ILLINOIS, ASSIGNOR TO HERBERT S. MILLS, OF CHICAGO, ILLINOIS.

PHONOGRAPH-STOP.

1,308,447.

Specification of Letters Patent.

Patented July 1, 1919.

Application filed July 5, 1916. Serial No. 107,581.

To all whom it may concern:

Be it known that I, HENRY K. SANDELL, a citizen of the United States, residing at Chicago, in the county of Cook and State 5 of Illinois, have invented a new and useful Phonograph-Stop, of which the following is a specification.

My invention relates to improvements in phonographs and more particularly to the 10 control mechanism of phonographs the record tables of which are electrically driven. The specific object of the invention is to provide improved control devices for effecting the starting and stopping of the electric motor by which the record table is 15 driven. The invention will be fully understood from the following specification taken in connection with the accompanying drawings in which—

20 Figure 1 is a top plan view of a phonograph embodying my invention; Fig. 2 is a transverse section through the case of the machine, taken on the line 2 of Fig. 1; Fig. 3 is a similar section taken on the line 3 of 25 Fig. 1, parts of the mechanism being shown in elevation; Fig. 4 is a sectional view taken transversely of the table-shaft and showing the construction of the current-interrupting device mounted thereon; Fig. 5 is an enlarged detailed section through one of the 30 brushes of the current-interrupting device shown in Fig. 4; Fig. 6 is a section on the line 6 of Fig. 2, the casing being removed; Figs. 7 and 8 are enlarged plan views showing 35 two positions of the combined switch and brake mechanism; Fig. 9 is a section on the line 9 of Fig. 8; Fig. 10 is a section on the line 10 of Fig. 1; and Fig. 11 is a 40 diagrammatic view showing the electric connections of the motor.

Referring more particularly to the drawing, the numeral 12 designates a generally 45 rectangular box-like casing which houses the working parts of the machine. Upon the bottom of this casing there is mounted a frame casting 13, which provides bearings for the vertical table-shaft 14, the latter being held in its assembled position with reference to the frame by a collar 15 secured 50 thereon by a set-screw, as shown in Fig. 3. The table-shaft is shouldered adjacent its upper end, which projects outwardly through the top of the casing, the shoulder serving to support the table 16, which is of 55 the usual disk form as to its upper surface,

and adapted to support upon its felt facing 17 a record-disk 18, which is centered and held in position by the projecting end of the table-shaft, as in ordinary phonograph constructions.

The table 16 is preferably formed of cast-iron and carries integral depending lugs 19 suitably spaced apart and extending downwardly through the aperture in the casing cover. The lugs 19 constitute armature 60 poles of the driving motor of the machine, being arranged in a circle to successively pass in front of the pole-pieces 20 of a U-shaped electromagnet, the legs of which are wound with coils 21, 22, the magnet being 65 supported horizontally in the plane of the lugs 19 by the frame casting 13, as is shown in Figs. 3 and 6.

Between the collar 15 and the lower step-bearing the table-shaft 14 carries a current-interrupting device, such device being in the 70 form of a metallic drum 23, insulated from the table-shaft by a bushing 24 and having inset in its cylindrical surface a row of insulating plugs 25, equal in number to the lugs 75 19. For coöperating with the drum 23 there are provided brushes 26, 27, vertically disposed, one above the other, and supported in the insulating block 28 carried by the frame 13. From Fig. 5 it will be seen that 80 each of the brushes 26, 27 is provided with a bore 29 in the end adjacent the drum, which bore receives the spring-held contact 30 of the brush. The brush 26 contacts with the drum 23 in the plane of the insulating 85 plugs 25, while the brush 27 bears upon the lower uninterrupted surface of the drum to constantly make contact therewith.

Bolted to a suitable boss on the frame 13 and arranged horizontally in the plane of 90 the table-lugs 19 is a horse-shoe magnet 31 (Fig. 6), the poles of which are spaced apart a distance equal to the space between adjacent lugs 19, so that the attraction exerted by the magnet will cause the table to come 95 to rest at the position shown in Fig. 6, with a lug opposite each of the legs of the magnet 31. This magnet is so related to the electro-magnet poles 20 as to cause the lugs 19 nearest adjacent the electro-magnet poles 100 105 to occupy the position shown in Fig. 6.

The combined switch and brake mechanism of my phonograph is shown in detail in Figs. 7, 8 and 9. This mechanism comprises a stud 32 mounted in a plate 33 fas- 110

tened to the upper face of the casing and carrying on such upper face a thumb-wheel 34 by means of which the stud may be manually operated. Beneath the plate 33 the stud 5 has pinned thereto an arm 35, which has pivotally mounted on its outer end a bent lever 36, one end of which projects upwardly through a slot 37 (Fig. 1) in the plate 33 and carries a friction block 38 adapted to 10 contact with the periphery of the table 16, being normally held in engagement with the table by a small tension spring 39 having one end engaged with a pin on the lever 36 and the other end with a pin on the arm 15 35, as is shown in Figs. 7 and 8. The end of the lever 36 opposite that which engages the table is wedge-shaped and is provided with a notch 40 which is adapted to engage a pin 41 projecting through an insulating 20 block 42 mounted beneath the plate 33. The arm 35 is normally held in the position shown in Fig. 7 by a small coil-spring 43 extending between a pin on the arm and a pin 44 (Fig. 9), secured in the plate 33. As 25 will be clear from an inspection of Figs. 7 and 8, rotation of the stud 32 in a counter-clockwise direction will cause the wedge-shaped extremity of the lever 36 to slide over the pin 41 until the notch 40 engages 30 the pin, in which position the parts will become automatically locked. A small electromagnet 45 is supported with its poles adjacent the wedge-shaped extremity of the lever 36 in this locked position of the latter, and the lever is constructed of magnetic 35 metal or has secured thereto a magnetic metal armature which, upon the energizing of the magnet 45, will be attracted toward the latter against the force of the spring 39 40 to disengage the notch 40 from the pin 41 and permit the spring 43 to draw the parts back to the position in which they are shown in Fig. 7.

The speed-regulating means for my motor 45 comprises an electro-magnet 50 (Fig. 2), suitably supported by the casting 13 and having a spring-leaf 51 supported at one end and overlying the pole of the magnet, the leaf preferably having secured thereto a 50 magnetic metal armature 52, which lies directly above but out of contact with the pole of the magnet 50. The effective length of the spring 51 may be altered by adjustment of a sliding abutment 53, which travels 55 beneath the leaf adjacent the fixed end thereof, the abutment being arranged for adjustment along the length of the leaf as by the screw 54, the outer end of which projects through the casing 12 and is provided with a knurled wheel 55 for convenient manual operation. A pair of insulating blocks 56', mounted above the fixed end of the spring 51, have sandwiched between them a contact-plate 57, which extends 60 outwardly parallel to the spring, and the up-

per of the two blocks 56' is preferably extended forwardly to provide a journal in which is mounted a counterweighted contact-lever 58. The lever 58 carries a vertically disposed carbon brush 59 in its outer end, the brush being designed to normally bear with a slight pressure on the upper face of the plate 57. For actuation of the lever 58 from spring 51, the former carries a downturned toe-piece 60, the end of which 75 clears the face of the spring 51 in the position which the latter occupies when at rest.

The automatic stop mechanism for my phonograph is best shown in Figs. 1 and 10, from which it will be seen that the pivoted tone-arm 61, which is adapted to swing across the face of the record in the well understood manner, carries a pin 62, to the outer end of which is secured an insulated sleeve 63. A small face-plate 64 is mounted 80 in the arc of movement of the contact member 63 and carries a stationary contact in the form of an eccentric 65 mounted upon a thumb-wheel shaft 66. A spring interposed between the plate 64 and the nut on the end 85 of the thumb-wheel shaft exerts a sufficient longitudinal pressure upon the shaft to cause it to remain in any angular position in which it may be set by manual operation of the thumb-wheel. 95

The electrical connections of the phonograph are illustrated by the diagram (Fig. 11), from which it will be seen that the power lines, designated 70, 71 and energized from any suitable source of current supply, 100 are, in general, connected in series through the switch, speed-regulator, motor and current-interrupting device. The automatic stop device 63, 65 is connected in shunt with the parts mentioned and in series with the 105 release magnets 45 of the switch. Both of the coils 21, 22 of the motor electro-magnet are in series with the current-interrupting device 23, but the coil 22 is shunted around the speed regulator, only the coil 21 being 110 in series therewith. A condenser 75 is shunted around the speed regulator to minimize sparking at the contact points thereof.

The operation of the mechanism described is as follows: Assuming that the phonograph is at rest, and that it is desired to operate the same, the thumb-wheel 34 of the starting switch will be rotated in a counter-clockwise direction, as viewed in Figs. 7 and 8. By such rotation of the thumb-wheel 34 the table 16 will be started in a clockwise direction, by reason of the movement of the friction surface 38 in the spring-held lever 36, the friction surface serving as a driving member. As the thumb-wheel approaches the limit of its counter-clockwise movement, the wedge-shaped extremity of the lever 36 will engage the insulated pin 41, and since the face-plate 33 which carries the thumb-wheel shaft and its connected 120 125 130

parts is in circuit with the electro-magnets 21, 22, and the insulated pin 41 is connected with the line wire 70, as illustrated by the diagram, the circuit will be established 5 through the operating parts of the mechanism. At its limit of movement the wedge-shaped extremity of the lever 36 is locked to the pin 41 by the notch 40, as shown in Fig. 8, so that the switch remains closed, the 10 circuit being completed therethrough.

As indicated by the diagram, the coil 22 of the electro-magnet is now in circuit with the energized lines 70, 71 through the interrupter 23, and the latter is so arranged that 15 with the parts in the position shown in Fig. 6, the brush 26 bears upon the surface of the drum between two of the insulating plugs 25. The lugs 19 nearest the poles 20 of the electro-magnet are therefore attracted to the 20 said poles, causing the table to be operated in a clockwise direction, as shown in Fig. 6. As the lugs reach a position opposite the poles 20, an insulating plug 25 rides under the brush 26 to interrupt the circuit, and by 25 the momentum of the table the latter continues to revolve until the next adjacent lug has come into position to be acted upon by the magnetism of the poles 20, at which time the insulating plug 25 will have traveled 30 past the brush 26 to permit the latter to once more complete the circuit and energize the magnet. The electro-magnet co-operating with the depending lugs or poles 19 of the table, and controlled by the commutator 23 35 therefore constitutes a simple type of electric motor for continuously driving the table 16 in a clockwise direction. The parts are so designed that the strength of the electro-magnet under the energizing current of 40 the coil 22 is just sufficient to rotate the table at the lowest speed required of the latter under operating conditions.

While the magnet-coil 22 is energized immediately upon the closing of the starting 45 switch, the magnet-coil 21 is likewise so energized, this circuit being completed by the carbon brush 59 of the contact lever 58 and by the contact plate 57, as illustrated in Fig. 11. Since the coil 50 of the speed regulator 50 is likewise in series with the interrupter 23, the current through the coil will be constantly made and broken at a speed depending upon the speed of rotation of the table. Such intermittent energizing and deenergizing of the coil 50 will cause the latter to 55 intermittently attract and release the spring armature 51 supported above the same. It is well known that oscillatory or vibratory devices of the character of the armature 51 60 have, by virtue of their proportions, mass, and elasticity, a certain natural periodic time of vibration or oscillation. If intermittent impulses of a frequency differing substantially from the natural frequency of 65 the vibrating element be impressed thereon,

very slight motion of the vibratory element will take place, but as the impressed impulses approach the natural period of the vibratory element, the amplitude of motion of the latter will become greatly increased. 70 It is upon these well known principles that my speed-regulating device operates. As the frequency of the electrical impulses impressed upon the coil 50 by the commutator 23 increases, and approaches the natural 75 frequency of the spring armature 51, the latter will begin to vibrate, and the amplitude of its vibrations will increase until at each vibration it is contacting with the toe 60 of the contact lever 58, raising the latter 80 and breaking the circuit between the brush 59 and contact plate 57. At this critical speed, therefore, the circuit of the magnet coil 21 is interrupted during a portion of the cycle of movement of the vibratory leaf 51, 85 and the mean effective value of the current in the coil 21 is thereby decreased. The amount of this decrease will be dependent upon the amplitude of oscillation of the vibratory armature 51, for the reason that in 90 general the periodic time of the oscillating contact lever 58 will considerably exceed that of the spring 51, and the brush 59 will therefore remain out of contact with the plate 57 not only during the time required 95 for the spring 51 to complete that portion of its movement which lies in range of movement of the toe 60, but also during the greater time required for the lever to return to its normal position after it has been lifted 100 by the spring. In practice, therefore, I am able to effect complete control of the current in the coil 21 by means of the vibrating armature 51, it being quite possible for the armature to vibrate with such amplitude as 105 to keep the brush 59 entirely out of contact with the contact-plate 57. It will be quite clear from the foregoing that the power of the magnet poles 20, and consequently the speed of the table 16, is a factor of the 110 periodic time of the spring armature 51. To adjust the speed of the table it is therefore sufficient to vary the periodic time of the vibratory armature, which may be conveniently effected from the exterior of the 115 phonograph through the knurled wheel 55, by means of which the sliding abutment 53 may be advanced or retracted to change the effective length of the spring. The control thus provided is exceedingly delicate. 120

As the tone-arm 16 is fed across the face of the record by the sound-reproducing grooves therein, the contact member 63 will approach the eccentric 65, and if the latter has been properly adjusted the parts will engage when the end of the record is reached. Such engagement will close the shunt circuit through the release magnets 45, as is indicated in Fig. 11, and by the energizing 125 of these magnets the lever 36 will be un- 130

latched from the contact pin 41, whereupon the spring 43 will exert its force to draw the arm 35 back into the position in which it is shown in Fig. 7. By this automatic release 5 of the starting switch the motor will be de-energized and simultaneously the friction surface 38 will act as a brake upon the table to bring the latter quickly to a stop. It may here be noted that the permanent magnet 31 10 will cause the table, in general, to come to a rest in the position most advantageous for again starting the same. The stationary magnet is, however, merely supplementary to the starting switch, the preferred con- 15 struction of the latter by which the table is manually rotated simultaneously with the closing of the circuit being in itself sufficient provision for the starting of the machine. Since the friction surface 38 is sub- 20 ject to wear, however, and may therefore be uncertain in action, after long service, I prefer to provide the electro-magnet 31 as an additional measure of precaution. By the use of this magnet, which prevents the 25 motor from coming to rest on a "dead point," the mere act of closing the circuit would at all times be sufficient to start the motor.

It may be noted as characteristic of my machine that the particular form of electric motor which I have shown and described is of peculiar advantage in phonograph constructions, by reason of the fact that the table is inherently of great weight, and therefore serves as its own fly-wheel, 35 preventing or minimizing those speed variations which are peculiarly fatal in phonographs because of their effect upon the pitch of the sound which is reproduced.

While I have shown and described in considerable detail one specific embodiment of my invention, it is to be understood that such showing and description is illustrative only and for the purpose of making clear the nature and objects of the invention, and 45 that I do not regard the invention as limited to this particular construction nor to any feature thereof except in so far as I have included such limitations within the terms of the following claims, in which it is my 50 intention to claim all novelty inherent in my invention as broadly as is permissible in view of the prior art.

What I claim as new and desire to secure by Letters Patent is:

1. In a phonograph, the combination with 55 a record table and a tone-arm adapted to swing in an arc thereabove, of a brake mechanism mounted adjacent the edge of said table and having a lever provided with an arm having a friction surface adapted to 60 engage the edge of said table, a spring connected with said lever for normally maintaining such engagement, means for holding said friction surface in inoperative position while a record is being played, an electromagnet coacting with said means, means for manually releasing said friction surface and simultaneously imparting a starting impulse to said table, a plate provided with a cam-slot for guiding said arm to cause the 65 friction surface to impart such starting impulse and then move out of contact with said table, and a contact mechanism actuated by said tone-arm and electrically connected with said electromagnet to release 70 said friction surface holding means and permit the application of said brake when the playing of a record has been completed.

2. In a phonograph, the combination with 80 a record table and a tone-arm adapted to swing in an arc thereabove, of a brake mechanism mounted adjacent the edge of said table and having a lever provided with an arm having a friction surface adapted to 85 engage the edge of said table, a spring connected with said lever for normally maintaining such engagement, a latch coacting with said lever for holding said friction surface in inoperative position while a record is being played, an electromagnet co- 90 acting with said latch; means for manually releasing said friction surface and simultaneously imparting a starting impulse to said table, a plate provided with a cam-slot for guiding said arm to cause the friction sur- 95 face to impart such starting impulse and then move out of contact with said table, and a contact mechanism actuated by said tone arm and electrically connected with said electromagnet to release said latch and 100 permit the application of said brake when the playing of a record has been completed.

HENRY K. SANDELL.
